UNITED STATES PATENT OFFICE.

WILLIAM T. MERSEREAU, OF SOUTH ORANGE, NEW JERSEY.

DESIGN FOR A BEDSTEAD.

SPECIFICATION forming part of Design No. 22,864, dated October 31, 1893.

Application filed October 2, 1893. Serial No. 487,031. Term of patent 7 years.

To all whom it may concern:

Be it known that I, WILLIAM T. MERSEREAU, a citizen of the United States, residing at South Orange, Essex county, New Jersey, have 5 invented a certain new and original Design for Bedsteads, fully described and represented in the following specification and the accompanying drawing forming a part of the same.

This design consists in a novel shape for a 10 bedstead; and is embodied in the annexed drawing which presents a perspective view of such bedstead.

The bedstead comprises the rectangular frame *a* with upright posts *b* at the front corners and similar posts *b'* at the rear corners. The front posts are connected by two cross-pieces *c* and *d* both arranged above the frame and joined by the series of parallel rods *e* to 15 form a grating at the head of the bedstead.

The rear posts are connected by the cross-piece *c'* above the frame *a* and the cross-piece *d'* below the said frame; such cross pieces 20 being connected together by the series of rods

e' which are bent outwardly adjacent to the frame *a* forming a recess at the foot of the 25 bedstead at the level of the said frame.

The essential feature of the design is embodied in a bedstead comprising a rectangular frame, and the upright rear posts connected by a cross-piece above and another 30 cross-piece below the said frame, such cross-pieces being joined together by a series of upright rods each curved outwardly adjacent to the said frame.

Having thus set forth the nature of the de- 35 sign, what I claim herein is—

The design for a bedstead herein shown and described.

In testimony whereof I have hereunto set my hand in the presence of two subscribing 40 witnesses.

WILLIAM T. MERSEREAU.
